UNITED STATES PATENT OFFICE.

CHARLES F. W. SEIDEL, OF NEW YORK, N. Y., ASSIGNOR OF ONE-THIRD TO CHRISTIAN BECK, OF SAME PLACE.

APPARATUS FOR SWEEPING STREETS AND REMOVING DIRT THEREFROM.

SPECIFICATION forming part of Letters Patent No. 349,816, dated September 28, 1886.

Application filed May 28, 1885. Serial No. 166,913. (No model.)

To all whom it may concern:

Be it known that I, CHARLES F. W. SEIDEL, of the city and county of New York, in the State of New York, have invented a new and 5 useful Improvement in Apparatus for Sweeping Streets and Removing Dirt Therefrom, of which the following is a specification.

My invention relates to that class of street-sweeping attachments which comprise a frame-work supported by an axle and pair of wheels, an endless carrier having an upward travel, and a rotary brush for delivering dirt upon the carrier, the frame-work of the apparatus being furnished with means whereby it may be 10 readily connected with a dirt-cart so as to form an attachment thereto.

The invention consists in a novel combination of parts in an apparatus of the kind above described, as particularly hereinafter described, and pointed out in the claim.

In the accompanying drawings, Figure 1 is a side view of the apparatus, one of the supporting-wheels thereof being removed, and also showing in section an apron or shield covering 25 the apparatus and a portion of the dirt-cart represented in dotted outline. Fig. 2 represents a plan of the apparatus, the apron or shield which forms an exterior covering therefor being removed to illustrate clearly the 30 parts beneath; and Fig. 3 is a plan of a part of the frame and one of the hooks.

Similar letters of reference designate corresponding parts in all the figures.

A designates a portion of the cart body or 35 box, and A' one of the wheels thereof.

My improved apparatus comprises two side frames, B , which may be made of cast or wrought iron, an axle, C , on which these side frames are supported, and wheels C' , which 40 may be of any suitable construction, and are fast upon the axle. These wheels may have teeth or ribs a upon their peripheries, as represented in Fig. 2, so that their rotation will be insured as they move over the ground, and 45 as the apparatus is drawn along the wheels and the axle rotate in unison.

In the lower portions of the side frames, B , is journaled a drum or roller, D , and in the upper portion thereof is journaled a second drum or roller, D' . Around these two drums or 50 rollers passes an apron, belt, or endless car-

rier, E , which may be made of canvas, sheet metal, or other material, and which has secured upon its face transverse lags or shelf-like projections b , extending from side to side 55 thereof. The side frames, B , also have portions which extend forward over the cart-body A , and have journaled in their extreme forward portions a third drum or roller, D' , around which the belt or carrier E is passed in its 60 travels.

Below and slightly rearward of the drum or roller D' is arranged another drum or roller, D^3 , around which the return portion of the belt or carrier passes, and which should be 65 notched or grooved longitudinally upon its surface to accommodate the lags or shelf-like projections b of the belt or carrier.

Upon the journal or shaft of the drum or roller D' is placed a chain-driving wheel, c , 70 which may have a polygonal or toothed periphery, and fast upon the axle C is another chain-driving wheel, c' . An endless driving-chain, c^2 , passes around the wheels c c' and transmits rotary motion from the axle C to 75 the upper apron drum or roller D' , which, in turning, imparts a progressive motion in one direction to the apron or carrier E , moving it in the direction indicated by the arrows in Fig. 1.

From the above description it will be understood that the arrangement of the drums or rollers D' D^2 D^3 is such that the dirt and refuse which is carried upward by the upwardly-moving operation of the belt or carrier is carried forward over the cart-box A , and by the passage of the belt or carrier around the drum or roller D^2 is deposited in the cart, and by the roller D^3 the returning portion of the belt or carrier is caused to move rearward nearly 80 horizontal until it clears the back of the cart-box and then moves downward to the drum or roller D .

Upon the shaft or axle which supports the lower drum or roller, D , is loosely pivoted a 95 guard or conductor, d , which rests upon the ground and has a curved upper face. This guard or conductor has its face continuous throughout the width of the apparatus, and has upwardly-projecting arms which are 100 loosely pivoted on the shaft of the roller D , and are constructed to enable the apron or car-

rier E to pass between them and clear the upper edge of the guard or conductor.

Upon the driving-axle C are loosely pivoted at opposite sides of the apparatus levers or arms F, which form at their outer ends bearings for the brush G, extending across the apparatus and free to rotate in the bearings. This brush may be of wire, rattan, or other suitable material, and in construction it may 10 be similar to the brushes of street-sweepers heretofore used.

At one side of the apparatus and upon the driving-axle C is secured fast a gear-wheel, e, and in one of the levers or arms F is fixed a 15 stud, f, on which turns freely a gear-pinion, e', which gears with and receives motion from the gear-wheel e.

Secured fast to the pinion e', so as to rotate in unison therewith, is a chain-wheel, e'', and 20 on the brush-shaft is a second chain-wheel, e'', and the chain-wheel e'' and brush G are continuously rotated in the direction of the arrow in Fig. 1 by a chain e' driving from the wheel e'' onto the wheel e''. The rotation of the 25 brush in the direction of the arrow, Fig. 1, picks up the dirt and throws it rearward and against the guard or conductor d, and by said guard or conductor the dirt is directed upward upon the belt or carrier E, and is 30 thereon retained by the lags or shelf-like projections b, and prevented from sliding off as the carrier moves upward.

To raise the brush temporarily from the ground, I have shown rods g' as connected with 35 the front ends of the arms or levers F. These rods are connected at their upper ends by a cross-rod, with which is connected a lever, H, which is fulcrumed at g to one of or between the side frames, B, and which, when depressed 40 by the driver, will lift the brush free from the ground and hold it temporarily in an elevated position.

In order to prevent the dust and dirt from 45 being blown or flying away from the apparatus while in operation, I have represented an apron or shield, I, which may be carried over rods or supports i, attached to the main frame, and which may be drawn down at the sides and attached to the side frames, B.

50 I have in Fig. 1 shown the side frame, B, as having buttons o for securing the apron, shield, or hood to it. The lower end of the apron is connected with arms I', which are loosely fulcrumed upon the shaft of the lower drum 55 or roller, D, and to these arms are applied coiled springs i', which exert a constant tendency to tighten the apron upon its supports i, consequently the apron will not interfere with the raising of the brush G, and when the 60 brush returns to its normal position the apron will automatically tighten upon the supports i and will serve its purpose of preventing the dirt from flying away.

At the lower part of the apron or hood I is 65 an opening, through which the brush works.

At the upper end of the apparatus this apron

may be carried downward and attached to the cart-box, and in order to prevent the dirt from being blown away as it is delivered into the cart side plates, I², may be arranged as shown 70 in dotted lines, Fig. 1, so as to cover the sides of the upper part of the apparatus. In Fig. 2 I have only shown the brush shaft or body, in order to show the guard d.

For attaching the apparatus to the cart-body 75 A, I have here represented hooks J, one only of which is shown, and which are pivoted to the side frames, B, at j. These hooks engage with projections a* on the cart-body and hold the apparatus to the body while in operation. 80 By means of stop-pins a² the hooks will be prevented from falling below the position in which they will engage with the projections a*, and their front ends or noses are inclined so that when the apparatus is pulled up against 85 the back of the cart-body the hooks J will rise over the projections a* and engage automatically therewith. I have also represented buffers or bumpers s as provided upon the main frames B of the apparatus, and which 90 will prevent any shock by reason of the apparatus striking against the rear end of the cart-box.

I have shown in Fig. 3 a plan of a part of the frame B, cart A, and the hook J connecting them, all being shown in side elevation in 95 Fig. 1.

From the above description it will be understood that my improved apparatus is simple and inexpensive in construction, and 100 may be readily disconnected from one dirt-cart when the latter is filled and connected with an empty cart for use therewith.

The chain and chain-wheels e'' e' e constitute 105 gearing whereby the carrier drum or roller D' is driven from the axle C, and the wheels e e' e'' e² and chain e' constitute gearing for driving the brush G from said axle.

Wire ropes or other flexible driving bands or connections may be substituted for the 110 chains and would be the equivalent thereof, suitable pulleys being substituted for the chain-wheels.

What I claim as my invention, and desire 115 to secure by Letters Patent, is—

The combination, with the side frames, B, and an axle and wheels for supporting them, of the endless carrier and its supporting and operating drums journaled in said frames, a rotary brush for delivering dirt upon the 120 carrier, rods i, connecting the side frames, and an apron or shield, I, covering the apparatus between the side frames, supported by the rods i, and having at one end a spring-connection whereby it is drawn and held taut over 125 the said rods, substantially as herein described.

CHARLES F. W. SEIDEL.
